Patented Nov. 14, 1922.

UNITED STATES PATENT OFFICE.

MAHLON E. LAYNE, OF SOUTH PASADENA, CALIFORNIA.

ELECTRIC DRIVE MECHANISM FOR ROTARY WELL PUMPS.

Application filed July 25, 1921. Serial No. 487,470.

To all whom it may concern:

Be it known that I, MAHLON E. LAYNE, a citizen of the United States, residing at South Pasadena, in the county of Los Angeles and State of California, have invented a new and useful Electric Drive Mechanism for Rotary Well Pumps, of which the following is a specification.

This invention relates to electric drive mechanism for rotary well pumps and is particularly directed to a drive mechanism in direct connection with the pump shaft.

The object of the invention is to provide a drive mechanism having two or more directly connected electric power units vertically aligned in superposed relation with the lowermost unit mounted in axial alignment with the well and each superposed unit entirely supported by the next lower unit.

Another object is to provide a drive mechanism comprising a plurality of vertically aligned superposed electric power units detachably united and arranged to permit the installation of additional units or the removal of one or more units to vary the available power of the mechanism in accordance to the required output and height of lift.

Another object is to provide a mechanism by which several stock units of the same or different sizes may be variously combined to meet the horsepower requirements of the pump, which requirements vary with variations in the depth to which the pump is positioned in the well.

A further object is to provide a vertical electric motor and a superposed table bracket for supporting a second motor, with the frame of the first motor provided with a seat upon which the bracket rests in true axial alignment with the motor shaft, the bracket being provided with means for attaching the second motor in true axial alignment with the first motor.

Various other objects and advantages will be more fully apparent from the following description of the accompanying drawings which form a part of this disclosure, and which illustrate a preferred form of embodiment of the invention.

Of the drawings:

Figure 1 is a side elevation, partly in section, of two superposed vertical motors and the intermediate table bracket.

Fig. 2 is a side elevation of the table bracket.

Fig. 3 is a top plan view of the table bracket.

Fig. 4 is a section on line x^4-x^4 of Fig. 2.

Fig. 5 is a section through a well bore showing the pump and the motor in elevation and illustrating various installations of the drive mechanism.

Fig. 6 is an enlarged detail section illustrating the means of attaching the bracket to the motor frame.

Before describing in detail the provisions for supporting one motor upon another, a brief outline of the advantages derived from such arrangement will be set forth, especially in its relation to economy of installation and its flexibility as to the wide range of available power.

It will be understood that the horsepower available for driving the pump shaft must vary coincident with variations in the output of the pump and the depth of the water level below the surface. Further it will be pointed out that in different wells in the same general locality the lift of one may vary considerably from the lift of others and that from long usage of a well or for other reasons the water level may lower continually or suddenly even to the extent of a hundred or more feet below the original water level.

It will therefore be evident that to provide a driving mechanism universally adaptable to meet these varying conditions it is highly desirable that such mechanism be adjustable as to the horsepower output.

In the present invention such adjustability is provided by forming the driving mechanism of interchangeable motor units which may be variously combined to produce a wide range of driving horsepower and by which additional units may be installed or one or more units removed to vary the available horsepower, without discarding the entire mechanism as originally installed.

By way of illustration, assuming that one well requires a 50 H. P. drive, another a 100 H. P. drive and yet another a 75 H. P. drive, the first may be provided with one 50 H. P. motor or if such is not available two superposed 25 H. P. motors may be installed. The second may be provided with two superposed 50 H. P. motors and the third with one 25 H. P. motor superposed upon one 50 H. P. motor.

Further if the water level of either of the

wells should lower to an extent requiring additional available horsepower an additional 25 H. P. or 50 H. P. motor as required will be mounted upon the motors 5 originally installed and the drive shaft, shaft casing and discharge casing lengthened to lower the pump suction pipe again below the water level.

From a standpoint of economy the interchangeability of the motor units assumes a major degree of importance for two reasons.

First, it being evident that to increase or decrease the horsepower of the driving mechanism it is only necessary to install additional units or to remove certain of those already installed instead of discarding the entire driving mechanism and substituting a single new motor of greater or less horsepower. Second, the number of different sizes 20 of motors which the jobber must keep in stock is materially reduced as with the present arrangement the jobbers can supply all usual demands with 25 H.P. and 50 H.P. motors.

25 In pumping wells utilized for drawing water or other liquids from the earth and of the general arrangement illustrated in the drawings a well casing 1 is driven down into the water bearing strata, and positioned 30 within the well casing near the bottom of the well is a rotary or centrifugal pump 2 having a suction pipe 3 extending below the water level. The pump comprising one or more pump bowls is attached to the lower 35 end of a discharge casing 4 extending upwardly and supported by a discharge head 5 at the surface. The pump shaft 6 extends upwardly through the discharge head 5 and through a shaft casing 7 which provides a 40 conduit whereby lubricant may be supplied to the various shaft bearings and the pump.

The driving mechanism is supported upon the discharge head and in the present invention such driving mechanism consists of 45 two or more superposed vertical electric motors in direct connection with the pump shaft 6 with each motor entirely supported upon the next lower motor in true vertical alinement.

50 As illustrated in Fig. 5, the lowermost motor 10 is supported upon a housing 11 with its drive shaft 12 connected to the pump shaft by any suitable form of coupling 13, said coupling preferably being of a flexible type which may be easily and quickly disconnected.

With the motor 10 of a sufficient horse power to lift the water from the initial water level of the well, the well may be 60 pumped as long as said water level remains at its initial point, but in case the water level lowers to such a point that the pump is no longer effective, the pump must be lowered by applying additional lengths of discharge 65 casing 4, pump shafting 6, and shaft casing

7, to the upper end of the string to again bring the pump into proper relation with the altered water level.

It will be evident that such lowering of the pump in the bore of a well or in mine 7 drainage work increases the lift and that a greater driving horsepower will be required to operate the pump which will be increased in capacity coincident to such increased lift, preferably by applying additional pump 75 bowls or units to the pump.

In the present arrangement, instead of following the prior method of removing the driving motor and substituting a motor of greater horsepower, the first installed motor 80 is retained and an additional motor 15 is mounted thereon in superposed relation by means of an intermediate table bracket 16, with the drive shafts axially alined and joined by a preferably flexible coupling 17 85 (see Fig. 1).

The specific type of motor herein illustrated has a base 20 a main frame 21, and a cover plate 22 having a bearing hub 23. The frame 21 is attached to the base by bolts 90 24 and ordinarily the cover plate 22 is attached to the frame by bolts 25. To adapt such motors for use in the present invention the bearing hub 23 is turned concentric with the drive shaft and the cover plate 22 95 is turned to provide a concentric alining shoulder 26 and a true horizontal seat 27 adjacent the bolt receiving bosses 28.

The table bracket 16 is of a shape somewhat similar to the general shape of an 100 "hourglass" and has a sleeve like lower end 30 turned to accurately fit the alining shoulder 26 and horizontal seat 27, a reduced center portion 31 bored to fit the bearing hub 23, and a circular top flange 32 all 105 joined to form an integral unit, by circular connecting webs 33, 34 and vertical strengthening ribs or fins 35. The webs 33, 34 have ventilation apertures 36 and the flange 32 is provided with a plurality of apertures 38 110 to receive the bolts 39 by which the upper motor 15 is secured to the table bracket. The lower sleeve end 30 of the bracket has a plurality of vertical bolt holes 40 spaced coincident to the spacing of the bolt holes 115 of the cover plate 22 and the table bracket is secured in place upon the cover plate by bolts 41 which extend through the holes 40 and the bolt holes in the cover plate and engage into screw-threaded bolt holes in the 120 motor frame.

With this arrangement the cover plate is secured to the motor frame and the table bracket to the cover plate by a single series of bolts which replace the bolts 25 with 125 which the motor is initially provided.

By the above described structure I have provided an electric drive mechanism for rotary well pumps, which comprises two or more power units mounted in superposed 130

relation one upon the other in various combinations to meet the horsepower requirements of the well pump, with the elements constructed to produce an automatic true vertical alinement of the units and to provide for a quick and easy assembling or disassembling of the parts for repair or for other reasons.

While it will be evident to those skilled in this art that the embodiment herein shown and described is of a preferable form, it will also be understood that it is susceptible of various modifications and changes without departing from the broad scope of the invention as set forth in the following claims.

I claim:

1. In a device of the nature disclosed, the combination including two superposed vertical motors, and an intermediate table bracket resting upon the frame of the lower motor and supporting the upper motor in true axial alinement with the lower motor.
2. In a device of the nature disclosed, the combination with a vertical motor having a frame and a top bearing plate, of a table bracket resting entirely upon the bearing plate and adapted for supporting a second motor in axial alinement with the first motor, and a single series of bolts attaching the bracket to the bearing plate and the bearing plate to the frame of the lower motor.
3. In a device of the nature disclosed, the combination with a vertical motor having a frame, of a table bracket resting entirely upon the motor frame and adapted for supporting a second motor in axial alinement with the first motor, means attaching the bracket to the frame of the first motor, and means attaching the second motor to the bracket.
4. In a device of the nature disclosed, the

combination with a vertical motor having a horizontal seat and a concentric alining shoulder, a table bracket having a sleeve portion engaging said seat and said shoulder and an upper flange adapted to support a second vertical motor, and a series of bolts attaching the bracket to the first motor.

5. In a device of the nature disclosed, the combination with a vertical motor having a cover plate providing a concentric bearing hub and having a horizontal seat, a table bracket engaging said seat and having a central bore engaging the bearing hub, and a single series of bolts attaching the bracket to the cover plate and the cover plate to the motor frame.

6. In a device of the nature disclosed, the combination including two superposed vertical motors and an intermediate table bracket, the lowermost motor being formed to axially aline the bracket therewith and the bracket having means supporting the second motor in axial alinement with the first motor, means for attaching the bracket to the first motor, and means for attaching the second motor to the bracket.

7. In well mechanism of the character described the combination of a pump disposed within a well, power transmission and water discharge means extending from the pump to the top of the well, a power unit for the pump, and means whereby an additional length of power transmission and water discharge means and an additional power unit may be added to lower the level of the pump without discarding the aforesaid parts.

Signed at South Pasadena, California, this 19th day of July, 1921.

MAHLON E. LAYNE.
